UNITED STATES PATENT OFFICE.

THOMAS B. LEE, OF BARNWELL, SOUTH CAROLINA.

COTTON-GIN.

SPECIFICATION forming part of Letters Patent No. 600,287, dated March 8, 1898.

Application filed August 31, 1896. Serial No. 604,402. (No model.)

To all whom it may concern:

Be it known that I, THOMAS B. LEE, a citizen of the United States, residing at Barnwell, in the county of Barnwell and State of 5 South Carolina, have invented certain new and useful Improvements in Cotton-Gins; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 My invention is an improvement in the class of cotton-gins in which a series of toothed cylinders are arranged to coact in such manner as to separate the fiber from the seed, bolls, and any foreign substances carried by the 20 cotton.

The novel features are hereinafter set forth.

The invention is illustrated in the accompanying drawings, in which—

Figure 1 is a plan view of a cotton-gin constructed in accordance with my invention, the brushes and conduits for conveying the cotton being shown by dotted lines. Fig. 2 is an inverted plan view showing by dotted lines the main driving-pulley, the belt for actuating the same, and the means for driving the brushes. Fig. 3 is a vertical central sectional view of the gin. Fig. 4 is a plan view of the means for supporting the main shaft of the machine. Fig. 5 is a plan view of the 25 support for the brushes, showing the adjustable bearings for the brush-shafts. Fig. 6 is a plan view of one of the plates for supporting the saw-cylinders, showing the adjustable bearings for the cylinder-shafts. Fig. 7 30 is a diagram showing the gearing for transmitting motion from the main driving-shaft of the gin to the saw-cylinders.

The main frame of the gin is made up of uprights A, which in the present embodiment 45 of the invention are three in number—the frame for the support of the lower end of the main driving-shaft, the plates for supporting the lower ends of the saw and brush shafts, and the plate carrying the bearings for the upper ends of these shafts. The uprights are 50 preferably of metal and T-shaped in cross-section, this form giving strength and rigidity

to the structure and affording convenient means for the attachment of the other parts of the gin.

55

B represents the main driving-shaft of the gin, and it is provided with a band-wheel b, over which passes a belt b' for giving motion to the shaft, with a pulley-wheel b², from which the brushes are driven, and with the 60 two spur gear-wheels b³ and b⁴, which mesh with intermediate gears, which in turn mesh with gear-wheels on the shafts of alternate saw-cylinders. The lower end of the main driving-shaft is supported in a bearing c, arranged in the center of a spider-frame C, the outer ends of which frame are attached to the uprights A by bolts c'. The saw-cylinders D, of which there may be any desired number, are preferably arranged in a circle, of which 70 the main driving-shaft is the center, and they are so mounted that their peripheries are only a short distance apart, there being a chamber E formed between the cylinders for the reception of the cotton to be ginned.

75

The lower ends of the shafts D' of the saw-cylinders D have their bearings attached to one or the other of the plates F or F'. These plates have circumferential flanges f for the reception of bolts f', by which they are attached to the uprights A of the frame of the gin. The plates F and F' are arranged a short distance apart, and each has attached to it bearings for one-half of the saw-cylinders employed, the arrangement being such that 85 shafts of alternate cylinders are mounted in the respective plates in order to give space for the gearing to be described hereinafter. Each bearing G is attached to one of the plates by bolts g, passing through slots f², cut radially in the plates, whereby the radial adjustment of the bearings may readily be accomplished. The upper plate F' has radial slots f³ through it for the reception of the shafts D', which have their bearings in the plate F, 95 and both plates have radial slots f⁴ for the accommodation of the shafts of the brushes presently to be described.

90

The saw-cylinders D receive motion from the main driving-shaft B through the gear-wheels b³ and b⁴, respectively, the gear-wheels d, with which each saw-cylinder shaft is provided, and the intermediate gear-wheels H. The intermediate gear-wheels are mounted

100

on the plates F and F' and are arranged in suitable bearings h, which are attached to the plates by bolts h', passing through slots in the plates, whereby the adjustment of the 5 intermediate gear-wheels to correspond to that of the saw-cylinder shafts is permitted.

The saw-cylinders D, whose operating-surface is of the usual construction employed in gins, are arranged in a chamber composed of 10 the plates I and J, the former forming the bottom of the chamber and the latter the top thereof. On the upper surface of the plate J are adjustable bearings G' of the same construction as those (G) described for the lower 15 ends of the saw-cylinder shafts D', by which the upper ends of these shafts are retained and by which they may be adjusted to correspond to the adjustment of their lower ends.

Arranged in positions to contact with the 20 outer faces of the saw-cylinders are the brushes K, by which the fiber separated from the seed and other matter by the saw-cylinders is swept from the saws and conveyed to the condenser L. Extending from each brush to 25 the condenser L is a conduit l, through which the fiber removed from the saws by the brushes is carried by the blast from the brushes to the condenser.

The brushes K are arranged on shafts K', 30 which are mounted in adjustable bearings k of the same construction as those of the saw-cylinders and as already described. The upper bearings k' of the brush-shafts are in the plate J, while the lower bearings are in the 35 plate K². This plate K² corresponds in construction and mode of attachment to the plates F and F', already described, and it is attached to the frame by bolts at a point a short distance below the plate F. Each brush-shaft is provided with a pulley k², around 40 which passes a belt k³, which bears upon and receives motion from the band-wheel b² on the main shaft B.

The upper end of the main shaft has a bearing 45 in the plate I, and on the lower face of this plate is also mounted the condenser-shaft M. Motion is given the condenser-shaft from one of the saw-shafts through the worm or helix m on the saw-shaft and the 50 gear-wheel m' on the condenser-shaft, which latter meshes with the worm or helix. The gear-wheel m' is attached to the shaft by a set-screw, permitting its adjustment to conform to the change of position of the saw-shaft.

Extending from the lower portion of the chamber E is a chute e, by which seed, bolls, or other substance separated from the fiber are conducted from the machine.

60 In the operation of the gin motion is imparted to the main shaft B, and this motion is, through the means hereinbefore described, communicated to the saw-cylinders and to the brushes. The cotton to be ginned is fed into the chamber E, Fig. 2, and the same is at once 65 formed into a roll by the action of the saws, which, as described, all rotate in the same di-

rection. The roll is kept rotating rapidly and fiber on the outer face is engaged in turn by the respective saws and carried to the 70 brushes, by which it is removed from the saws and carried to the condenser through the conduits by the blast from the brushes. The spaces between adjacent saw-cylinders is too small to allow seed, &c., to pass with the fiber, 75 and the same falling by gravity enters and discharges through the chute e, whereby the fiber is left in a condition entirely free from objectionable matter. The action of the saws is after the manner of combing and the fiber 80 is not subjected to cutting or to strain. Consequently the desirable long fiber of the staple is preserved. Choking or clogging at the point where the fiber is drawn from seed, &c., which might result in injury, is prevented in 85 a gin constructed according to my invention for the reason that any excess of cotton engaged by one saw-cylinder will at once be caught and moved along by a succeeding saw-cylinder, thus leaving to each saw only a 90 quantity of fiber which may with safety be drawn between adjacent cylinders.

Although I have particularly described my invention as applied to ginning cotton, it will be apparent that the same general construction may with advantage be applied to machines for delinting cotton-seed or for burring wool, and machines for these purposes constructed substantially as herein set forth are considered within the scope of my invention. 95

In adapting my device for the purpose of delinting cotton-seed the saw-cylinders would preferably be covered with card-clothing.

Having thus described my invention, what I claim as new, and desire to secure by Letters 105 Patent, is—

1. A cotton-gin comprising a main shaft provided with gear-wheels, a series of vertical saw-cylinders having their shafts provided with gear-wheels, being mounted in adjustable bearings, and gear-wheels interposed between those on the main shaft and those on the cylinder-shaft, the interposed gear-wheels being mounted in adjustable bearings, substantially as described. 110

2. A cotton-gin comprising a main shaft provided with gear-wheels, a frame having two horizontal step-supporting plates F and F', which are separated by a considerable space, and the upper one provided with slots, 120 a series of saw-cylinders and their shafts arranged concentrically with said main shaft, and each alternate saw-shaft passing through slots in plate F', and being stepped on the lower plate, F, the other shafts being stepped 125 on plate F', gears on the shafts, and intermediate gears meshing with those on the main and saw shafts, as shown and described.

3. A cotton-gin comprising a central, vertical, driving-shaft, a series of vertical saw-cylinders and their shafts arranged concentrically with said driving-shaft, fixed and adjustable gearing connecting all the said shafts, radially-slotted top and bottom plates

arranged in the frame of the gin, the end bearings G, G', for said cylinder-shafts, which are arranged on said top and bottom plates and secured by bolts passing through radial 5 slots in the latter, as shown and described.

4. A cotton-gin comprising a main shaft provided with gear-wheels, a series of concentrically arranged saw - cylinders and their shafts having a pulley and gear-wheels, and 10 bearings which are radially adjustable, the series of intermediate gears H, meshing with the gears of main and saw shafts and having the adjustable bearings h h', a series of

brushes and shafts arranged exteriorly to, but concentrically with, the saw-shafts, and provided with pulleys, and an endless belt passing around said pulleys and in contact with the pulley on the main shaft, as shown and described. 15

In testimony whereof I affix my signature 20 in presence of two witnesses.

THOMAS B. LEE.
